UNITED STATES PATENT OFFICE.

CHRISTIAN H. DORANG, OF POTTSTOWN, PENNSYLVANIA.

SURGICAL SPLINT.

1,177,398.

Specification of Letters Patent. Patented Mar. 28, 1916.

Application filed August 8, 1914. Serial No. 855,777.

To all whom it may concern:

Be it known that I, CHRISTIAN H. DORANG, a citizen of the United States, residing in Pottstown, Pennsylvania, have invented certain Improvements in Surgical Splints, of which the following is a specification.

My invention relates to that class of surgical splints which are used in connection with fractures of the forearm, and which have a hand grip at the forward end of the wrist portion of the splint, the object of the invention being to permit the use of the splint with equal comfort on either the right or the left arm.

15 In the accompanying drawings—Figure 1 is a face view of a splint constructed in accordance with my invention and having the hand grip adjusted as when the splint is used on the right arm; Fig. 2 is a similar 20 view showing the hand grip adjusted as when the splint is used on the left arm; Fig. 3 is a side elevation of the splint shown in Fig. 2; Fig. 4 is a transverse section on the line *a*—*a*, Fig. 2; and Fig. 5 is a view similar 25 to Fig. 1 but illustrating a modification.

In the drawings, 1 represents the arm portion of the splint and 2 the wrist portion of the same, which are usually made of sheet metal and perforated as indicated, the arm portion being transversely bent or curved so as to partially envelop that portion of the forearm to which it is applied.

The wrist portion 2 of the splint is provided with a hand grip 3, whose normal position is diagonal to the axial line of the splint, and in order that the splint may be used with equal facility on either arm I pivot this hand grip to the wrist portion of the splint so that it may be adjusted at one angle when the splint is to be applied to the right arm or at an opposite angle when the splint is to be applied to the left arm, the grip thus conforming to the natural and comfortable position of the hand in either case.

The hand grip is carried by a right angled plate 4, which is pivoted to the wrist portion of the splint, and I find it preferable to laterally shift the pivot point of the grip in changing the same from the right hand position to the left hand position, for this reason the wrist portion of the splint is provided with two laterally separated openings 6 and 7 to either of which the pivot pin 5 can be applied, thus, as shown in Fig. 1 when the grip is adjusted for the right hand the

pin is applied to the pivot opening 7 on the left of the center, and when it is adjusted for the left hand position shown in Fig. 2 it is applied to the opening 6 on the right of the center.

The pivot plate 4 of the grip is also provided with means for locking the same in position after the grip has assumed its proper angular relation to the wrist portion 2 of the splint. The locking means shown in Figs. 1 and 2 consist of a pin 8 which may engage either of two openings 9 and 10 formed in the wrist portion of the splint, the pin engaging the opening 9 when the grip is adjusted for the right hand, as shown in Fig. 1, and engaging the opening 10 when the grip is adjusted for the left hand, as shown in Fig. 2.

The pin 8 may be separate either from the splint or the pivot plate 4 of the grip, but I prefer to secure it to one or other of them so that it will not be liable either to loss or displacement.

In order to provide for ready shifting of the pivot plate 4 of the grip from one to the other of the openings 6 and 7 the stem of the pin is preferably threaded for the reception of a nut 11 which bears upon the underside of the wrist portion 2 of the splint and can be readily removed when it is desired to shift the pin and as readily applied in order to retain the pin in proper position after adjustment.

In effecting the shift the pin 5 is first removed, the plate 4 is then lifted so as to withdraw the pin 8 from the opening formerly occupied by it, and the plate is then shifted so as to readjust the grip 3 and apply the pin 8 to the new opening in the splint, the pivot pin being then applied to its new opening and secured in position as before.

As shown in Figs. 1, 2 and 4 the pin 8 is carried by the pivot plate 4 of the hand grip and the openings 9 and 10 are formed in the wrist portion of the splint but it will be evident that the relation of the pin and openings may be reversed without affecting my invention. For instance, in Fig. 5 I have illustrated a splint in which a pin 8^a occupies a fixed position on the wrist portion of the splint and the openings 9^a and 10^a for the reception of said pin are formed in the pivot plate 4, the openings 6^a and 7^a for the reception of the pivot pin 5 being also formed in the pivot plate instead of in the

wrist portion of the splint, as in the constructions previously described.

I claim:

1. A forearm splint having a hand grip with pivot plate pivotally mounted upon the wrist portion of the splint, and a pin for locking said plate in either of its adjusted positions, one of the parts having a plurality of openings for the reception of the pivot pin and one of the parts also having a plurality of openings for the reception of the locking pin.

2. A forearm splint having a hand grip, a plate pivotally mounted upon the wrist por-

tion of the splint, and a pin for locking the plate in either of its adjusted positions, said wrist portion of the splint having a plurality of openings for the reception of the pivot pin and also a plurality of openings for the reception of the locking pin.

In testimony whereof, I have signed my name to this specification, in the presence of two subscribing witnesses.

CHRISTIAN H. DORANG.
